UNITED STATES PATENT OFFICE.

HARRY JONES, OF MAHWAH, NEW JERSEY, ASSIGNOR TO AMERICAN BRAKE SHOE & FOUNDRY COMPANY, OF MAHWAH, NEW JERSEY, A CORPORATION OF NEW JERSEY.

BRAKE-SHOE.

1,168,810.

Specification of Letters Patent. Patented Jan. 18, 1916.

Application filed November 23, 1915. Serial No. 62,941.

To all whom it may concern:

Be it known that I, HARRY JONES, a citizen of the United States, and a resident of Mahwah, in the county of Bergen and State 5 of New Jersey, have made and invented certain new and useful Improvements in Brake-Shoes, of which the following is a specification.

This invention relates to brake shoes.

10 In certain types of brake shoes, and particularly those containing hard sections, the metal, during service, tends to tear off and granulate, and the resulting small particles act as an abradant and cause the body of the 15 shoe to wear away in a rapid and uneconomical manner, and in addition also cause the body of the shoe to wear with small heat checks prevailing throughout the entire wearing surface, all of which materially reduce the serviceable life of the shoe. I have 20 found by numerous experiments that this tearing off and granulation of the hard metal of the shoe may be entirely prevented, and therefore the serviceable life of the shoe 25 materially lengthened by providing a material, incorporated in the body of the shoe, which, during service, will spread out and smear across the entire wearing face of the shoe, and, entering into the interstices or 30 pores of the cast metal, will cause the same to wear with a highly polished and burnished surface, and under which conditions the shoe operates at its maximum efficiency.

Other objects and advantages will appear 35 as the description proceeds, wherein it is to be understood that changes in the precise embodiment of the invention can be made within the scope of what is claimed without departing from the spirit thereof.

40 The preferred embodiment of my invention is disclosed in the accompanying drawings, wherein:

Figure 1 is a view in longitudinal vertical section of a brake shoe embodying the 45 characteristic features of my invention; Fig. 2 is a view in top plan of the brake shoe with a portion of the body thereof broken away.

Referring specifically to the several views, 50 the shoe therein illustrated is formed with the usual type of steel back 5, upon which the body of the shoe is cast, and with the key-attaching lug 6, by means of which latter the shoe is secured to a brake head. The

body of the shoe includes the wearing sections 7, 8 and 9, which may be formed entirely of hard metal, or may contain local chilled areas therein, according to the type of shoe and the class of service which it is to perform. Interposed between the sections 60 7, 8 and 9, are the supplemental sections 10 and 11, formed of a material which is adapted to flake off and smear across the entire wearing face of the shoe. Cast gray iron, containing a high percentage of free carbon 65 and graphite, forms an extremely efficient material for these supplemental sections, lead and aluminum, and several other metals acting with efficient results.

I do not necessarily limit myself to a shoe 70 wherein the supplemental sections are interposed between the wearing sections, nor to the specific arrangement illustrated in the several figures, it being only necessary that the supplemental sections be of such 75 extent and arrangement that the material of which they are composed will spread and smear across the entire face of the shoe, and, entering into the interstices and pores thereof, cause the shoe to wear with a highly 80 polished and burnished face.

What I claim is:

1. A brake shoe comprising wearing sections and a supplemental section extending entirely across the body of the shoe and 85 formed of a material adapted to smear along the wearing surface of the shoe and cause the same to wear with a high polish.

2. A brake shoe comprising wearing sections of gray cast iron containing a high 90 percentage of free carbon, extending entirely across the body of the shoe and adapted to cause the same to wear with a high polish.

3. A brake shoe comprising a wearing section of hard metal, and a supplemental section of gray cast iron containing a high 95 percentage of free carbon and extending entirely across the body of the shoe and substantially equal in thickness to that of the wearing sections.

Signed at Suffern in the county of Rockland and State of New York this 16th day of November A. D. 1915.

HARRY JONES.
